HENRY NAGEL AND JOHN E. NAGEL, OF BRUNSWICK, NEBRASKA.

PUMP.

No. 858,901.

Specification of Letters Patent.

Patented July 2, 1907.

Original application filed May 13, 1905, Serial No. 260,276. Divided and this application filed August 22, 1906. Serial No. 331,587.

To all whom it may concern:

Be it known that we, HENRY NAGEL and JOHN E. NAGEL, citizens of the United States, and residents of Brunswick, in the county of Antelope and State of Nebraska, have invented a new and Improved Pump, of which the following is a full, clear, and exact description.

This is a divisional application of our application for pumps, serially numbered 260,276, filed May 13, 1905, 10 and relates to driven or deep well pumps, in which a metal casing fixed in the earth has an inner lining in which the piston reciprocates, and in the lower part of which lining is fixed an upwardly opening check valve.

Our invention consists in a simple attachment to 15 this form of pump, whereby either a vacuum or the pressure of an air cushion is made to promote the continuity of the up-flow of water, as hereafter more fully described.

Reference is to be had to the accompanying drawings forming a part of this specification, in which similar characters of reference indicate corresponding parts in all the figures.

Figure 1 is a sectional view of a driven well having our attachment applied and acting as a vacuum chamber, and Fig. 2 is a fragmental view of the casing, lining and piston rod, showing our attachment connected to the top of the piston and acting as a compression chamber or air cushion.

In the drawing, Fig. 1, 1 is a well casing having an 30 inner lining tube 2 within which operates the piston 3 having an upwardly opening valve 4 and a piston rod 5 rising to the surface.

Below the piston and carried by the stationary packing ring 6, is the usual casing 7, supporting an upwardly 35 opening check valve 8. The lower extremity of this check valve casing 7 is screw-threaded internally to receive our attachment. This consists of a cylinder 9 screw-threaded both at its upper and lower ends, and across which near the top is a partition 10 dividing it 40 into an upper and lower chamber. Above the partition 10, openings 11 in the side walls of the cylinder connect the annular space formed between the cylinder 9 and the outer casing with the interior of the check valve casing, while below the partition 10 openings 12 45 lead from said annular space into a vacuum chamber 13 situated below the partition 10.

With a pump equipped with our attachment, the operation is as follows: When the piston 3 rises, air is

first drawn out of chamber 13 and then water follows and is drawn up through the check valve 8, said water 50 passing up from the well through the annular space around the cylinder 9 and through the openings 11. As soon as the air is exhausted from chamber 13, only water then rises, and the suction of the piston above produces at the same time a suction and partial vacuum 55 in the chamber 13. Then on the downward movement of the piston, when the check valve 8 closes, the vacuum in chamber 13 will assert the suction effect and cause the water to continue to enter the well tube. This is of special value when the water has to pass through 60 small holes in the well tube or point, or when the inflow of water is small, since it prolongs the inflow of water through the period of time when the piston is descending as well as when it is rising.

In Fig. 2 we show exactly the same construction of 65 cylinder 9 with partition 10 and holes 11 and 12 above and below the partition. The cylinder 9 in this case, however, is attached to the top of the piston 3 and between the same and the piston rod 5, and when the piston descends the water rushes up through holes 11 and 70 12 and compresses air cushions above the holes 12 and 11, which in expanding force the water up around the cylinder 9 past the piston rod 5 to prolong the up-flow above the piston.

Having thus described our invention we claim as 75 new and desire to secure by Letters Patent:

1. An attachment for pumps, consisting of a cylinder having a partition across it with openings above and below said partition, and a screw-threaded upper end adapted to connect either with the check valve casing or piston rod to 80 form a vacuum or compression chamber.

2. An attachment for pumps, consisting of a cylinder having a partition across it with lateral openings above and below the partition, and a screw-threaded upper and lower end adapted to be connected between the piston rod 85 and piston or to the check valve below the piston to form a vacuum or compression chamber.

3. An attachment for pumps consisting of a cylinder having a partition across it with openings above and below said partition, in combination with the pump casing and check valve casing and stationarily connected to the check valve casing below the check valve to form a vacuum or compression chamber.

In testimony whereof we have signed our names to this specification in the presence of two subscribing witnesses. 95
